G. F. VOIGHT

WIRE FASTENER

Filed July 29, 1925

Fig. 6.

INVENTOR
George F. Voight

UNITED STATES PATENT OFFICE.

GEORGE F. VOIGHT, OF OAKLAND, CALIFORNIA.

WIRE FASTENER.

Application filed July 29, 1925. Serial No. 46,805.

My invention relates to improvements in wire fasteners particularly adapted for attaching metal lath, in spaced relation, to the wall sheathing of stucco structures, although 5 also useful for other purposes.

One of the objects of the present invention is the provision of novel spacing means carried on the shank of a nail, the spacing means adapted to be disposed intermediate 10 the wall sheathing and the lath, and the nail adapted to be driven into the wall sheathing and to bind the lath against the spacing means; a further object is the provision of spacing means comprising a fibrous 15 cushioning disk and a metal binding cap supported thereby; with the foregoing and still further objects and purposes in view which will appear as the description proceeds, my invention resides in the combination 20 and arrangement of parts and in the details of construction hereinafter described and claimed, it being understood that changes in the precise embodiment of the invention herein disclosed can be made within 25 in the scope of what is claimed without departing from the spirit of the invention.

In the accompanying drawings—

Figure 1 is a side elevation of a wire fastener constructed in accordance with my 0 invention, disposed in driving position against the face of a portion of the wall sheathing, preparatory to driving it thereto, and a cross section of a portion of metal lath;

Figure 2 is a view similar to the preceding figure but with the nail now driven into the wall sheathing as far as it is intended to go, for binding the lath against the spacing means and the latter against the wall 5 sheathing;

Figure 3 is a vertical sectional elevation of the wire fastener in its permanent position attached to the wall sheathing, a cross section of a portion of lath confined between the nail head and the spacing means, and a section of stucco composition as applied thereto;

Figure 4 is a view on line 4'-4' of Figure 2;

Figure 5 is a plan view of the cushioning disk; and

Figure 6 is a perspective view of the binding cap.

Referring to the drawings in detail,

throughout which like reference characters 55 designate like parts:

The numerals 1, 2 and 3, designate the nail, binding-cap and cushioning disk, respectively, of my improved wire fastener, and the numerals 4, 5 and 6, designate the 60 wall sheathing, metal lath and the stucco composition, respectively.

The wall sheathing 4 constitutes the backing against which the stucco composition 6 is spread and which may comprise the usual 65 boards nailed across the face of the studing or other members forming the framework of the walls, or the like, of stucco structures, adapted to receive a coating of stucco composition, or, the same may comprise any 70 suitable substitute for said boards.

7 designates building-paper, which is preferably disposed across the face of the wall sheathing 4 to prevent exterior moisture 75 penetrating to the wood-work of the structure and also to separate the stucco composition from the wall sheathing to prevent deterioration of the latter by chemical action set up by contact with the former.

The several elements comprising the present wire fastener, are preferably assembled 80 at the factory, in the order shown in Figure 1, wherein they are ready for attachment to the wall sheathing for securing the lath thereto.

The cushioning disk 3, which is disk-shaped and preferably formed of fibrous material to make it more or less yielding to impact or pressure, is provided with a central opening 8, through which projects the 90 pointed end of the cylindrical shank of the nail 1, which nail is provided at its opposite end with the usual disk-shaped head.

The diameters of the nail shank and the opening 8 are intended to be such, relatively, to cause the shank to bear against the walls of the opening with sufficient pressure to resist removal therefrom, but resistingly slideable through said opening 100 when the cushioning disk is seated against the wall sheathing into which the nail is operatively driven.

The binding cap 2, which is formed of thin sheet metal, is cup-shaped, has a flat bottom 9 provided with a central opening 105 10, and has its upper edge or rim formed with pointed spurs or teeth 11.

The opening 10, which receives the nail 1,

is preferably made large enough to permit free movement of the binding-cap on the nail, both longitudinally and rotatably. The binding-cap is prevented from slipping off 5 the end of the nail by the cushioning disk 3.

The metal lath 5 may comprise any of the conventional type of metal lath, including the metal lath commonly known as "poultry netting", or any other suitable wire, 10 or wire fabric.

To apply my improved wire fastener for attaching metal lath to the wall sheathing of a stucco structure, the fastener is preferably grasped by its upper end and its forward end projected through a suitable mesh 15 of the lath and disposed against the wall sheathing along one side of one of the wires forming the mesh, with the spacing means disposed between the lath and wall sheathing, (see Fig. 1), the nail is then driven 20 forward into the wall sheathing until the head of the nail engages and binds the lath wire against the binding cap 2 and the latter and the cushioning disk firmly against 25 the wall sheathing (see Fig. 2).

The fasteners may be disposed along on the lath at such intervals as may be found best suited to the type of lath employed and as may otherwise be found best suited 30 to the peculiar work to be performed. I have found by practice that spacing the fasteners about eight inches apart provides ample fastening for most types of metal lath at present used for stucco reinforcement.

After the lath has been suitably attached to the wall sheathing, the stucco composition is preferably applied by spreading it on the wall sheathing and on and around the lath 40 and the exposed portions of the fasteners.

As the building-paper 7 simply forms a protective outer coat or shield for the boards forming the wall sheathing and may be considered to form a part thereof, the 45 term or designation "wall sheathing" as used in this specification may at times be intended to include the building-paper. For instance, when it is stated that the fastener is disposed against the wall sheathing, it is to be understood that the latter 50 includes the building paper.

The cushioning disk 3, which is adapted to function as means for retaining the loosely fitting binding cap 2 on the nail shank, and as a cushion between the binding cap and the building-paper 7, as well 55 as forming part of the spacing means, is preferably formed of fibrous material impregnated with a suitable preservative to prevent deterioration from contact with the stucco composition.

The cushioning disk being yieldable acts 60 as a cushion for the metal binding cap 2 and prevents this member from injuring the building-paper when the fastener is brought

in contact therewith as when projecting it through the lath or when driving the nail for attaching the fastener to the wall sheathing. The cushioning disk also acts as a seal 70 between the nail shank and the building-paper and between the stucco composition and the building-paper for preventing water or moisture passing to the opening made therethrough by the nail when driven into the wall sheathing.

The lath wire 5 is intended to seat in two of the depressions 12 between a division of the spurs 11. The binding cap being movable on the nail shank permits it to rotate thereon and thereby adjust itself to 80 the lath wire in case the latter does not fully register with two of the depressions 12 when brought into engagement with the binding cap by the head of the nail when the nail is operatively projected into the wall 85 sheathing for attaching the lath.

In case it is found that the space between the wall sheathing and the lath is greater than desired, the binding cap may, by giving the nail an extra blow or two with the 90 hammer, be caused to collapse or partly collapse under the increased impact, thereby decreasing said space to the extent desired.

While I prefer to cut the cushioning disks 3 out of sheets of card-board, or paper-board, of suitable thickness, they may, if so desired, be formed by moulding the fibre composition in suitable moulds, or they may be formed in any other way found expedient.

I claim:

1. A device for securing metal lath to a support in spaced relation thereto, comprising, a fibrous element adapted to bear against said support, a metallic element adapted to bear against said fibrous element, 105 and a nail projecting through said elements.

2. A device for securing metal lath to a support in spaced relation thereto, comprising, a fibrous element adapted to seat against said support, a metallic element adapted to seat against said fibrous element, and a nail projecting through said elements, said fibrous element bearings against said nail to 110 resist removal therefrom.

3. In combination, an element of relatively soft material, a lath engaging element formed of sheet metal seated thereon, and a cooperable driven element having a shank projecting through both said elements and bearing against the former to normally resist removal therefrom.

4. A device for securing metal lath to a support in spaced relation therewith, comprising, a nail provided with a cylindrical head at its upper end, an element secured to said nail to resist removal therefrom, an element on said nail intermediate said first named element and said head, one end of said nail adapted to be projected into said support to cause said head to engage and 125

bind a lath wire against said last named element and to bind the latter and said first named element against said support.

5. A device for attaching wire lath to a support, in outstanding relation thereto, comprising, a paper cushioning disk adapted to seat against a support, a binding cap seated on said cushioning disk, and a nail passing through both said cap and disk, 5
10 said nail having a lateral projection at its upper end adapted to engage and bind said wire lath against said cap, said nail adapted to be projected a distance in said support for securing said cap and disk there- 15 against.

6. A multi-element device for attaching lath to the wall sheathing of a structure, in spaced relation thereto, comprising, an element adapted to form a seat for said lath, 20 a nail passing through said element, said nail having a head at its upper end adapted to engage and seat said lath on said element, an element carried on said nail to resist removal therefrom, said last named 25 element adapted to limit the movement of said first named element on said nail in one direction.

7. A multi-piece device for attaching metal lath to the wall sheathing of a structure, comprising, a binding cap having an 30 opening, a headed nail projecting slidably through said opening, upwardly extending projections on said cap, said head adapted to engage and bind said lath on said cap between said nail and one of said projections, and means carried on said nail below 35 said cap and to normally resist removal therefrom, said nail adapted to secure said cap and means to said wall sheathing, said 40 means adapted to hold said cap from bearing against said wall sheathing when said

nail is driven therein for securing said cap and means thereto.

8. A device for securing metal lath to the wall sheathing of a stucco structure, in 45 spaced relation thereto, comprising, a cushioning disk formed of card board, a binding cap supported thereby, a cooperating nail projecting through said disk and cap, said nail having a head, said cap having a projection on one side, said nail operatively 50 slidable relative to said disk and cap for causing said head to engage and bind said lath against said cap between said nail and said projection.

9. A device for securing metal lath to a support in spaced relation thereto, comprising, a cushioning disk formed of paper composition and having an opening, a cup-shaped binding cap seated on said disk and 60 having an opening in its bottom in axial registration with said first named opening, the rim of said cap being serrated to form 65 a plurality of pointed spurs, a nail projecting through said openings, said nail having a head over-lying said spurs, said head adapted to engage and bind said lath on said cap between a division of said spurs, said nail adapted to be driven in said support. 70

10. In combination, a solid cushioning element having a flat side adapted to seat against a support, a lath supporting metallic element adapted to seat against the opposite flat side thereof, and a nail projecting 75 through said first named element and bearing thereagainst to normally resist removal therefrom.

In testimony of the foregoing being my own, I have hereunto affixed my signature this 24th day of July, 1925.

GEORGE F. VOIGHT.
